UNITED STATES PATENT OFFICE

THOMAS B. TARN, OF PITTSBURGH, PENNSYLVANIA

PROPELLUTION OF VESSELS

Application filed October 25, 1929. Serial No. 402,415.

My invention pertains to the propulsion and maneuvering of barges, ships and other water-borne craft by means of a jet or jets of a gas (usually air), under pressure which is caused to react in an orifice or orifices, and to further react on the hull structure of the vessel and surrounding water. The principal object is the provision of such a jet propulsion means, simple in arrangement and effective in operation, and which has an increased efficiency, as to the propulsion effect produced per unit of applied power, over jet propelling devices as heretofore proposed.

A further object of the invention is to provide a system of control for maneuvering the vessel, by which steering, flanking, twisting operations and lateral movements necessary to properly, efficiently and safely handle the vessel, or its attending tow, are accomplished in an effective manner.

A still further object of the invention is to accomplish the efficient propulsion and effective maneuvering of the vessel by eliminating the usual under-water and superimposed parts, such as, screw propellers, paddle wheels, rudders, stern-posts, struts, and the like.

Other objects of the invention will appear more fully in the below detailed description of a preferred embodiment of my invention, which description is to be taken solely as illustrative and not in any sense limiting.

The invention, as recited, consists substantially in the construction, combination, location and relative arrangement of parts, all as will be more fully hereinafter set forth and shown in the accompanying drawings and finally pointed out in the appended claims.

By way of illustration, I have described in the following specification a vessel, in this case, a barge, equipped with propulsion means according to my invention, and shown the same schematically in the accompanying drawings, in which:

Fig. 1 is a side elevation of a vessel, with the stern half in section, showing diagrammatically the relative arrangement of the parts embodying the principles of my invention;

Fig. 2 is an end view, looking toward the stern, illustrating a vessel when provided with two independently arranged orifices.

Fig. 3 is a top plan view of the forward section of the vessel and a sectional plan view of the stern section of the vessel.

Similar reference characters refer to similar parts throughout the several views of the drawings.

The problem of safe, efficient and economical navigation has in recent years received great attention and study. Power generating units for watercraft have been brought to a high state of efficiency by the utilization of refined heat conserving apparatus. However, despite the above named progress, comparatively little advancement has been made in the methods and practices adapted for applying the power generated for propulsion purposes. It is the purpose of this invention to obtain the benefits and advantages made possible by the provision of a simple, effective and efficient propulsion arrangement, whereby, as heretofore stated, the usual paddle wheels, screw propellers, rudders and their attendant supports and power operating mechanisms are dispensed with, and the power utilized in overcoming the resistance which these elements present to propulsion made available for utilization in a useful manner to add to the speed of the vessel, to decrease maintenance costs and increase operating security.

This invention accomplishes the desirable ends heretofore recited by the utilization of a fluid jet. Heretofore when fluid jets were used for propulsion, recourse was necessarily had to extremely high fluid pressures and velocities. It is my purpose to attain the desirable ends while utilizing a fluid jet and yet to dispense with the necessity of high fluid pressures and velocities. Scientific efforts made in this field of endeavor have conclusively shown that that means of propulsion is best, other things being equal, which drives or propels astern the largest mass or volume of water at the lowest velocity, or, in other words that the greater the quantity of water operated on by a jet the greater the efficiency thereof. With this principle as a

hypothesis, it immediately becomes apparent that efforts to obtain effective results at high pressures and velocities are of necessity doomed to failure and that to insure desirable results, recourse must be had to low pressures and velocities obtainable by the use of properly designed jets. It is my purpose to hereinafter disclose a jet having an orifice of large area and scientifically designed to secure high efficiency and great reaction in cooperation with a structure wherein the energy contained in the air or other fluid used, after such fluid has issued from the orifice may, by proper design in the form of the hull of the vessel, be made to operate on said hull and on a maximum quantity of water.

Referring now to my drawings, it will be seen that—

In the drawings, 10 indicates the hull of the vessel, which is formed, at its after end, with an inclined stern rake 11 which terminates in a horizontal portion 12, the latter being placed substantially at the load water line. A pair of elongated horizontally disposed orifices 13 are formed through the stern rake 11, usually close to the bottom of the hull, and each communicates with an air compressor 15, the latter being preferably constructed and arranged to deliver air as directly as possible to orifices 13. Each of the blowers 15 is provided with an electric motor 16, for driving the latter, the current for such motors being derived from a generator 17 driven from a suitable centrally disposed power plant 18. A valve, 19, is provided for each of the compressors 15 so that the air ejected from the individual orifices 13 may be controlled. The stern of the barge 40 is provided with four skegs 20 adapted to prevent the air from expanding sidewise, which, as shown, are constructed abreast the orifice openings and extend rearward from the stern rake 11 to form channels for confining and directing the air ejected from orifices 13, to a path in which they will have the greatest propelling efficiency. The advantageous effect of thus allocating my skegs is that were they not so arranged as to confine and direct the air issuing from the orifices, the slewing of the vessel, due to wave, wind or steering effect, would cause the air to escape laterally thereby reducing the volume of water which would otherwise be set in motion and become effective for propulsion purposes. It is, of course, obvious that the side press or skegs, as before pointed out, confine the issuing air in a sidewise direction, limit its movement laterally and thereby cause the expansion in volume to take effect in a downward rather than in a lateral direction, thus confining the action of the air to water of less disturbed state than that found on and at the surface.

The reaction of the jets of air issuing

from the rearwardly directed orifices 13 exerts a forward propelling effect on the vessel, and, according to my invention, I obtain desirable results in such propulsion by making the orifices 13 of a relatively large area 70 and so constructing and operating the compressors 15 that the air is ejected at a relatively low velocity, as, for example, by so proportioning the area of the orifices and the velocity of the jets of air issuing therefrom 75 that the velocity of such jets, relative to the vessel, is only about twice that of the designed velocity of the vessel itself. I have ascertained that a velocity of the discharged air, relative to the vessel, of from one and 80 one-half to four times the designed velocity of the vessel itself will give a satisfactory propulsion efficiency. Inasmuch as the impulse or reaction of a jet issuing from an orifice is double the hydrostatic pressure on the 85 area of such orifice; and, inasmuch as this is true independent of and apart from the nature of the fluid issuing from the jet and the nature of the medium into which it is issued, it is clear that a relatively high jet propulsive reaction is available under the stern end 90 of the vessel. It is apparent that when the jet reaction energy possible of extraction from the emitted fluid medium by this means is coupled in its application to the formed stern that the energy available, as pointed out hereinafter, due to the difference in specific gravity between the jet fluid medium and the medium into which the jet is discharged, to wit the water, at considerable depth below 100 the surface thereof, most effective propulsion is attained.

In addition to the propulsion resulting from the reaction of the jets, the air, in rising upward along the inclined plane constituted by the stern rake 11, and in expanding as they rise, have a further forward propelling effect. Such propelling effect is still further enhanced by the horizontal portion 12 of the stern, which confines the upward surge of water which would otherwise occur at that point and causes such surge of water to be directed horizontally astern, and thereby further increase the propelling effect without additional increase in power over that required to provide air for the jets. To make further use of the energy contained in the air jet issuing from the orifice, that is, the velocity-pressure energy, as well as the energy due to the difference in density between air and water and the necessarily attendant expansive characteristics thereof, the hull is so formed and shaped, as brought out in the drawings and disclosed above as to permit of unobstructed travel, expansion and reaction on the flat inclined and rearwardly extending portion of the hull structure as limited by the depth of submergence of the hull. The horizontal portion 12 is arranged so that it occurs at about, or above the intersection 125 130

of the water level with the continuation of the inclined portion of the hull structure, or stern rake aforementioned. To insure the horizontal rearward movement of the water set in motion by the air released under the stern rake, this section of the hull is extended horizontally rearwardly, runs parallel to the surface of the water and extends transversely for the full width of each orifice. This portion embodies the principles of stern construction set forth in my Letters Patent No. 1,346,279, for screw propelled chambered-stern towboat, dated July 13, 1920.

For steering the vessel, one or the other of the compressors 15 may be stopped, while the other continues to rotate, or, for a slight steering effect, one or the other of the valves 14 may be manipulated to reduce the amount of air ejected through the corresponding orifice 13. For backing the vessel, an orifice 21, extending horizontally across the bow, and arranged similarly to the orifices 13, may be provided, air for such orifice being supplied by means of an individual compressor 22. Likewise, for moving the vessel laterally, turning it upon a short radius, etc., side orifices may be provided at bow and stern and on the port and starboard sides, in a manner which will be readily understood from the foregoing.

It is to be understood, of course, that the mechanical means for carrying my invention into effect in connection with various types of vessel may be varied within wide limits, without exceeding the scope of the invention, as defined in the appended claims.

I claim:

1. A navigable vessel having adjacent inclined and horizontal stern portions, the inclined portion being substantially beneath the water level while the horizontal portion is substantially at the water level, an elongated and narrow fluid orifice mounted in said inclined stern portion and directed oppositely to the direction of propulsion, and means for discharging a fluid through such orifice.

2. A navigable vessel having adjacent inclined and horizontal stern portions, the inclined portion being substantially beneath the water level while the horizontal portion is substantially at the water level, an elongated and narrow fluid orifice mounted in said inclined stern portion and directed oppositely to the direction of propulsion, means for discharging a fluid through such orifice, and skegs secured to said inclined and horizontal stern portions for confining the emitted fluids.

3. The combination with a vessel having fluid passages leading through its stern and bow of means for forcing a fluid through said passages, and elongated narrow outlet orifices secured to said passages at the ends thereof

and extending substantially transversely of the longitudinal axis of the vessel.

4. The combination with a vessel having adjacent inclined and horizontal stern portions and fluid passages leading through its stern and bow of means for forcing a fluid through said passages, elongated and narrow outlet orifices secured to said passages at the ends thereof, and skegs secured to said inclined and horizontal stern portions for confining emitted fluid. 70 75

5. The combination with a vessel hull having a substantially flat bottom, an inclined plane surface joined to said bottom and extending upwardly to a point adjacent the rear end and a substantially flat plane surface extending from this point to the stern of the hull, of a series of spaced skegs secured to and projecting from said inclined and horizontal portions and extending longitudinally of the hull to form inverted channels, apertures arranged in the inclined portion aforementioned and opening into said channels, and means for discharging compressed fluids at a relatively low pressure through said apertures and into said channels, whereby when the hull is moving forwardly through the water said fluid will travel rearwardly along said channels, upwardly along the inclined plane, and rearwardly along the horizontal plane hull portion to increase the buoyancy of the vessel and drive it forward. 80 85 90 95

6. A navigable vessel having a substantially horizontal hull portion, an inclined upwardly extending stern portion joined to said horizontal hull portion, a horizontally extending supplementary stern portion joined to the stern end of said inclined portion, skegs secured to said inclined, last named, horizontal portion to form inverted channels, and elongated narrow air jets mounted in said inclined portion and directed oppositely to the direction of the propulsion of the vessel for propelling the same by directing air upwardly and rearwardly and then horizontally along the inclined and horizontal portions respectively. 100 105 110

In testimony whereof, I sign my name.
